UNITED STATES PATENT OFFICE.

EDMUND VOIGT, OF CHICAGO, ILLINOIS.

ELECTROLYSIS SUSPENSION HOOK.

Application filed February 12, 1923. Serial No. 618,618.

To all whom it may concern:

Be it known that I, EDMUND VOIGT, a citizen of the United States, residing at Chicago, in the county of Cook and State 5 of Illinois, have invented a new and useful Improvement in Electrolysis Suspension Hooks, of which the following is a specification.

My present invention is of the nature of 10 an improvement on the hook of my Patent No. 1,412,909, dated April 18, 1922, in the matter of its comprising longitudinally adjustable sections; and it also relates to providing the so-called "case" with means for 15 removably securing, in most advantageous position thereon, different sizes of the metal plates to be subjected to electro-deposition.

In the accompanying drawing, Figure 1 is a view showing my improved hook in 20 front elevation, having a suspended plate secured in set position in accordance with my improvement for the purpose, and Figure 2 is an edge view of the same.

The suspension-hook, which is designated 25 as a whole in the drawing by the reference-letter A, is shown to be formed of three lengthwise adjustable sections, 3, 4 and 5. The section 3, which is provided with the hook-like head 3^a, contains a central longitudinal slot 3^b. The section 4 has a bolt 7 in its upper end extending through the slot 3^b in the section 3 and carrying a wing-nut 7^a, whereby the two sections may be longitudinally adjusted, one with relation to the 30 other, and releasably fastened in adjusted position; and the section 4 contains a central longitudinal slot 4^a and terminates at its lower end in a pair of ears 8, from between which a metal shoe 9 is pivotally suspended and pressed, for the purpose herein-after explained, by a spring 10 extending from the face of the section 4. Either of 35 these sections is of metal, though it is preferred to have them both conductive of electricity. The third section 5 is of electrically insulating material, such as gutta-percha, and is expanded, as shown, at its lower end, where it carries the horn-like hangers 11; and this section carries a bolt 12 to pass 40 through the slot 4^a and through the lower end portion of the section 3, to enable the sections 4 and 5 to be longitudinally adjusted, one with relation to the other, a wing-nut 12^a on the bolt serving to releasably fasten the sections 4 and 5 in adjusted 45 position.

By forming the stem A of these three sections, they may be adjusted with extreme nicety to lengthen and shorten it for the immersion purpose referred to in the aforesaid 60 patent.

The "case" 13, preferably of electrically insulating material, such as gutta-percha, is provided with means for readily and releasably fastening in most advantageous position thereon different sizes of plates for receiving on their faces the desired electro-deposition of metal, by immersion, under suspension by the hook A in a suitable electrolyte. As the preferred means for this purpose, I provide the sheet 13 with numerous openings, shown as circular perforations 15 arranged in the staggered relation represented in Fig. 1, and adapted to receive button-like fasteners 16 for enabling the latter to be inserted through the perforations that occur nearest the edges of a plate 17 of given size, so that the button-heads may overlap the plate-edges and hold the plate 70 stably in position on the sheet. To adjust 75 a plate 17 in place, its upper edge is inserted under the folded upper end 13^a of the sheet, when the buttons 16 are applied to secure it in place, as shown and described; and when the plate-carrying sheet is hung on 80 the horns 11, the shoe 9 bears yieldingly, under pressure of the spring 10, against the face of the plate to hold the sheet rigidly against the adjacent portion of the face of the hook-section 5 and makes good electrical 85 contact with the surface of the plate 17, to which the electric current may be directed 90 by way of the stem in any desired manner.

As will be observed, the adjustment afforded by the lengthening and shortening 95 of the stem for regulating the depth of immersion of plates in the electrolyte, is supplemented by the provision for setting the plates on the sheet 13, whereby the extent in height of the latter to be subjected to the 100 electrolytic action may be gaged with extreme nicety. Either of these adjustments, however, presents its own inherent advantages.

I realize that considerable variation is 105 possible in the details of construction herein shown and described, and I do not intend by illustrating or describing a single specific or preferred embodiment of my improvement to be limited thereto, it being my intention in the following claims to claim 110 protection for all the novelty there may be

in my invention as fully as the state of the art will permit.

I claim:

1. A suspension-hook of the character described, comprising an electro-conductive stem formed of a series of sections adjustable longitudinally for lengthening and shortening it, the lowermost section being composed of insulating material and provided with case-hanging means, and a spring-pressed electrical contact-shoe on the last-named section.
2. A suspension-hook of the character described, comprising an electro-conductive stem formed of a series of three sections, of which the lowermost is composed of insulating material, the uppermost section having a longitudinal slot through which a bolt passes from the intermediate section, which contains a longitudinal slot through which a bolt passes from the lower section to render said sections relatively adjustable longitudinally for lengthening and shortening the stem.
3. In combination with an electrolysis suspension-hook, a plate-carrying sheet provided in its body with perforations, and means co-operating with said perforations for releasably securing in set position thereon plates of different dimensions.
4. In combination with an electrolysis suspension-hook, a plate-carrying sheet provided in its body with perforations and button-like fasteners adjustable in the perforations with their heads overlapping the edges of and releasably fastening a plate in set position thereon.
5. In combination with an electrolysis suspension-hook, a sheet having a folded upper edge and provided in its body with perforations, a plate on the sheet with its upper edge in the fold thereof, and button-

like fasteners in the perforations overlapping at their heads the edges of the plate to releasably fasten it in set position 45 on the sheet.

6. In combination with an electrolysis suspension-hook, a sheet having a folded upper edge and provided with staggered series of perforations, a plate on the sheet 50 with its upper edge in the fold thereof, button-like fasteners in the perforations overlapping at their heads the edges of the plate to releasably fasten it in set position on the sheet, and a spring-pressed shoe on 55 the hook to bear against the plate for electrical contact therewith and stably confine the sheet against the hook-stem.

7. In combination, an electrolysis suspension-hook having a stem formed of sections longitudinally adjustable for lengthening and shortening it, a plate-carrying sheet suspended on the lowermost stem-section and provided in its body with perforations, and means co-operating with said 65 perforations for releasably securing in set position on the sheet plates of different dimensions.

8. In combination, an electrolysis suspension-hook having a stem formed of sections longitudinally adjustable for lengthening and shortening it, a sheet having a folded upper edge and provided with staggered series of perforations, a plate on the sheet with its upper edge in the fold thereof, 75 button-like fasteners in the perforations overlapping at their heads the edges of the plate to releasably fasten it in set position on the sheet, and a spring-pressed shoe on the hook-stem to bear against the plate for 80 electrical contact therewith and stably confine the sheet against said stem.

EDMUND VOIGT.
